MARIUS LAVET, OF PARIS, FRANCE, ASSIGNOR TO ETABLISSEMENTS LÉON HATOT, OF PARIS, FRANCE, A CORPORATION OF FRANCE

ELECTROMAGNET

Application filed October 13, 1930, Serial No. 488,502, and in France October 17, 1929.

The present invention relates to improvements in electro-magnets (associated or not with electric contacts) and to their application to electric clocks and watches whether 5 self-contained or operated from a distance, provided or not with striking movements and chimes, and to various other apparatus such as chimes, vibrators, electric twinklers, polarized relays, battery charges, synchronous 10 motors, contactless rotating motors, loud speaker motors, pick ups, etc.

In the industries of electric clocks, telegraphy and wireless, electro-magnets are employed in many apparatuses which have an 15 alternating movement, these being principally employed for operating hands, for winding up springs, for operating electric contacts, etc.

The requirements for electro-magnets are 20 generally as follows:

1. Good electric efficiency, and small inherent resistances, the latter arising principally from sticking and magnetic attractions from inertia of the parts to be displaced and 25 from mechanical friction.

2. Simple construction and low cost of manufacture.

3. Small weight and reduced overall dimensions of the electro-magnet and reduced consumption, specially for portable time instruments such as automobile watches and clocks etc. and for time receivers disposed in the centre of translucent dials.

4. In several applications, good electrical 30 efficiency must be obtained for a very low supply voltage.

This last quality is in particular sought 35 for electric watches and clocks which must operate by means of a battery of small size lasting for a very long time.

In order that the lasting power shall be good (for example exceeding two years), it is found that it is advantageous, for given 40 overall dimensions, to use a battery of a single element (1^v, 5) rather than batteries of three elements (4^v, 5) like the batteries for pocket lamps. For the same consumption in watt hours, with a very slow rate of discharge, the duration is better. Calculation and 45 experience show that polarized electro-magnets

give the best results for utilizing the energy of the battery in question than ordinary soft iron electro-magnets. In all cases, the polarized electro-magnet systems employed hitherto, are bulky, heavy, and costly. Further 55 they comprise strong magnets which give rise to considerable friction and magnetic sticking. This is also caused by the fact that the conception of the shapes of their various constituent parts does not permit easy assurance 60 of the equality of the widths of air gap, and that in practice relatively large differences are found, producing lack of balance of the magnetic forces and much reducing the efficiency particularly when it is a question of 65 producing a relatively small mechanical power, as is the case for the application contemplated.

The present invention relates in the first place to improvements in very small polarized electro-magnets capable of being housed in the casings of large watches, such as automobile watches.

The details of construction and the shapes of the constituent parts enable all the members to be collected into a very restricted space, and permit the maximum use of first class materials in order to obtain a very high electric power in relation to the weight of the apparatus.

To obtain this last result, the actual state of the art shows that it is advantageous to employ:

1. A magnet of steel or cobalt such that the ratio between the length and the other 75 dimensions is preferably less than in magnets of horse-shoe type.

2. For the iron parts magnetized by the winding, silicon sheet metal, or electrolytic iron, or any other product having great 80 permeability and very small hysteresis (especially certain ferro-nickel alloys when the field is weak).

3. A winding of high conductivity copper with spires of as small a length as possible disposed to accommodate the maximum volume of copper.

4. Air gaps of large surface and small thickness permitting variation of the reluctance of the deformable magnetic cir- 100

cuits within very wide limits according to a predetermined law dependent upon the applications.

The magnetic products in question above 8 are very costly and further are only commercially profitable in certain forms (especially cylindrical rods and thin plates).

The invention enables these materials to be used in most favourable conditions and it 10 equally concerns various devices and applications of these systems associated with special electric contacts.

The object of the invention is set out in the following descriptions of various constructional forms which have been illustrated by way of example in the attached drawings.

On the drawings:

Figure 1 shows the usual method of constructing magneto-electric machines actually known.

Figures 2, 3 and 4 show in projection with parts in section, a polarized electro-magnet provided with improvements constituting 25 the object of the invention.

Figures 5, 6 and 7 are detail views of the constituent members of the electro-magnet.

Figures 8, 9 and 10 are diagrammatic figures showing the effect of the shape of the 30 pole pieces of the movable armature of the electro-magnet.

Figures 11 and 11b show a modification of the arrangement of the magnet.

Figure 12 shows diagrammatically the 35 application of the electro-magnet associated with an electric contact in an electrically wound clock or watch.

Figure 13 is a diagram of the electric circuit of the system shown in Figure 12.

Figure 14 shows separately the electric contact whose closure is automatically produced.

Figures 15 and 16 show the application 45 of the invention to time receivers operating by means of alternating emissions of the electric current.

The improvements forming the object of the invention relate more particularly to the 50 known type of polarized electro-magnet shown in Figure 1. This type of electro-magnet comprises a magnet A provided with heavy polar expansions A₁ and A₂ and a coil wound on an iron armature B rotating about the axis C. The coil is well known under the name of "Siemens shuttle". This system is employed as a motor, or as a current generator. In this last application, it is employed very frequently as the ignition magneto for explosion motors. Practice shows that the 55 electro-magnet constructed and proportioned as indicated in Figure 1 does not allow the advantageous production of sensitive electro-magnets and economic manufacture suited to electric clockwork and like applications. This is because when the movable ar-

mature of the apparatus of Figure 1 is rotated, very intense forces of magnetic attraction are exerted on this part which tend to rotate the coil in certain directions dependent on the shape of the pole pieces. These forces exist when the coil is not traversed by the electric current. They also persist when the coil is energized by a current and they prevent displacement when the current is weak. Displacement is only produced when the current is very intense and, even in this case, the driving couple obtained is irregular and the electrical efficiency is impaired because the value of the current has to be increased in order that the apparatus may overcome the inherent resistances for the positions corresponding to the minimum driving couple.

These disadvantages are eliminated with the improved method of construction described with reference to Figures 2, 3 and 4.

According to the invention, the electro-magnet consists of a magnet A, preferably of steel or cobalt, and a movable coil whose core N is of electrolytic iron or like metal whose coefficient of magnetic permeability is very high.

The coil is provided with polar enlargements B₁ and B₂ constructed of stamped and bent sheet metal. The metal constituting them must be of very high magnetic permeability and very weak hysteresis, (for example of silicon sheet or alloy of like properties).

The shape of the pole pieces is of very great importance, and it may be modified according to the applications. Generally it is desired that the coil be operated by a very weak current and that the driving couple be of a value which is very high and constant over considerable angular displacement. This result is obtained with the shapes and proportions shown in the drawings.

The movable coil pivots in holes cut in the two brass plates C₁ and C₂. These plates are 11 connected together by four iron pillars P₁, P₂, P₃ and P₄ which constitute the fixed pole pieces of the apparatus. These poles are connected magnetically to the magnet by the stamped angle pieces of sheet iron E₁ and E₂. These parts E₁ and E₂ are slightly flexible and they bear with heavy pressure on the polar extremities of the magnet and on the pillars P₁, P₂, P₃ and P₄. The use of the flexible parts E₁ and E₂ has the important advantage of permitting very weak reluctance of the joints and strong magnetization of the pillars to be obtained. This result is obtained without the necessity of having an extremely precise spacing of the limbs of the magnet. The magnets can consequently be less costly than if it was necessary to grind the magnet to a very exact size. The U shape of the parts E₁ and E₂ should also be noted. The parts E₁ and E₂ are shown separately in

perspective in Figure 7. The shape of the parts E_1 and E_2 also enables a sufficiently large free space to be preserved between the magnet and the movable coil. This space is employed to receive the flexible wires connecting the movable coil with the fixed terminals of the circuit. By bending back these connections on themselves and by making them of considerable length, the flexure of the wire is limited to a small value and a great flexibility is obtained; also breakage of the wire in spite of a large number of displacements of the coil is prevented.

The details of construction of the movable coil are shown in the detail views (Figures 5, 6 and 7). The two pivots O_1 and O_2 are riveted on two brass parts H_1 and H_2 connected together by two pillars D_1 and D_2 .

The pivots O_1 and O_2 engage the holes in the plates C_1 and C_2 .

The coil B is wound beforehand on the core which terminates in two threaded rods on which can screw the nuts G_1 and G_2 . These nuts permit the whole assembly of the constituent parts of the coil (that is to say, the brass parts H_1 and H_2 , the pole pieces B_1 and B_2 and the coil B) to be accomplished. To this end the outline of the parts H_1 and H_2 comprises tongues t and shoulders e . The tongues t engage exactly in recesses in the parts B_1 and B_2 and all the parts are maintained firmly in well defined emplacements and can be fitted up by suitable manipulations. It should be understood that certain changes may be made within the spirit of the invention. In particular the nuts G_1 and G_2 may be replaced by screws screwing into the core N .

It should be noted that this special method of construction has two particularly important advantages:

1. The play between the cylindrical pole pieces P_1 , P_2 , P_3 and P_4 and the movable parts B_1 and B_2 depend only upon these parts being produced by stamping. In effect the pivot hole and the three guide holes for the pillars P_1 , P_2 , P_3 and P_4 can be stamped simultaneously in the parts C_1 and C_2 .

The parts B_1 and B_2 are applied by locking of the nuts G_1 and G_2 on the parts H_1 and H_2 obtained by stamping. It is known that the method of manufacture by stamping enables very large series of parts which are exactly interchangeable being obtained.

2. This method of construction will thus permit very great accuracy being obtained, particularly in regard to the play or air gap between the pole pieces. This is very important, for practice shows that very slight differences in the values of the air gaps alter considerably the driving couple as well as the value of the magnetic attractions acting on the coil.

2. The parts constituting the magnetic circuit are only formed by cylindrical parts of

small diameter or by very thin sheet metal. The coil support is also constituted by very thin stampings. Consequently the maximum space is thus obtained for receiving the electric winding. This is particularly important for the production of very small electro-magnets, for theory and practice show that one can only obtain good efficiency on condition that the coil is made as long as possible. The parts stamped out in thin sheet metal are difficult to assemble rigidly for one cannot cut tapped holes in very thin metal. With the construction shown in Figure 7, the assembly is obtained by nuts G_1 and G_2 and small screw threaded pillars D_1 and D_2 , whereby perfect rigidity is obtained, even if the electro-magnet is given very small dimensions.

When the current is interrupted and the coil is rotated by hand, the magnetic attraction due to the magnet A and acting between pole pieces B_1 and B_2 and the iron pillars P_1 , P_2 , P_3 and P_4 , varies according to a certain law which depends on the variation of the total reluctance of the magnetic circuit with the angle of rotation. It is well known that in variable magnetic circuits natural direction of displacement of the movable part is such that it reduces the reluctance of the circuit to a minimum.

In the apparatus shown in Figures 2 to 6, the total reluctance of the magnetic circuit depends mainly on the reluctance of the air gaps, that is to say, on the air spaces bounded by the adjacent parts of the pillars P_1 , P_2 , P_3 and P_4 and of the pole pieces B_1 and B_2 . When the coil rotates, the reluctance of certain air gaps increases and that of other air gaps decreases. This variation depends both on the thickness of the air gap and on its area. Compensation for this variation can be obtained by giving the parts B_1 and B_2 a certain stamped shape and by centering these parts either concentrically with the axis of rotation O_1 , O_2 , or with a certain degree of eccentricity in order to vary the play or air gap with the angle of rotation.

The shape shown in Figure 6 permits the coil provided with iron enlargements B_1 and B_2 to be in neutral equilibrium in the internal magnetic field produced by the magnet A . This coil may be displaced by means of a very weak force. If the coil is brought to any point in its path it remains in position without having any tendency to return or to continue its movement. It should be noted that this result is obtained by shaping the sides of the pole pieces as arcs of circles m_1 , n_1 , q_1 and m_2 , n_2 , q_2 (Figure 6). Further, the angles m_1 , m_2 , q_1 and q_2 are slightly directed towards the centre as is indicated in Figure 6bis. The radius of the points R_1 is slightly smaller than the radius R_2 of the adjacent part of the core of the coil.

These shapes and proportions have been

determined experimentally. For certain applications it is advantageous to depart from the proportions indicated in Figures 6 and 6bis, in order to bring the coil in certain positions. Figures 8, 9 and 10 indicate by way of example the properties of three shapes of the pole pieces B_1 and B_2 .

If the mean arc formed by the pole pieces B_1 and B_2 is relatively small in relation to 10 the distance of P_1 and P_2 , as indicated in Figure 8, the mean position shown on this figure is a position of unstable equilibrium. When the current is stopped, the coil tends to be displaced either towards the left or towards the right, so that the pole pieces B_1 and B_2 come opposite to the poles P_1 and P_4 15 or the poles P_2 and P_3 .

If the mean arc formed by the pole pieces B_1 and B_2 is relatively large in relation to 20 the separation between P_1 and P_2 , as indicated by Figure 9, the mean position shown on this figure is a position of stable equilibrium. The coil tends of itself to come between the poles P_1 and P_2 under the influence of the 25 magnetic force of attraction due to the magnet.

Figure 10 shows such a shape for the pole pieces B_1 and B_2 that the coil tends to be displaced in the direction of the arrow f_1 . It 25 is sufficient to make the curvature of the pole pieces such as B_1 eccentric. The displacement tends to diminish the play with the pillar P_2 , or the air gap. This means may be combined with that of giving a certain stamped shape to the pole pieces B_1 and B_2 . The outline may be asymmetric. By adopting the proportions of the plan view, Figure 10bis, and by making R_1 very slightly less than R_2 , the result may be obtained 35 that the coil is brought back in the direction f_1 with a very small and constant force, as if a balanced part returned by a spring were used.

The magnet A only having the function 40 of strongly magnetizing the pillars P_1 and P_2 , P_3 and P_4 may be disposed in different manners. In particular, it may be placed as shown in Figure 11. To obtain a very high driving force with a weak current, it is desirable to increase the magnetic flux of the 45 magnet and to reduce the reluctance of the magnetic circuit. This double result is obtained by the arrangement shown in Figure 11bis which is a sectional view corresponding to Figure 11. It will be seen that two magnets A and A' disposed side by side are employed. The length of the pole pieces B_1 and B_2 in the direction parallel to the axis O_1 , O_2 is increased and this also increases 50 the surface of the air gap and enables a much greater electromagnetic force to be obtained than if the plates C_1 and C_2 were closer together, and than if there were only a single magnet employed.

Actually the manufacturers of power elec-

tro-magnets adopt similar forms. The apparatuses are produced by preserving the same proportions and by increasing all the dimensions. Consequently, none of the parts of one model can serve in larger models. 70

This disadvantage may be avoided by adopting the arrangement of Figure 11bis. For example the small model will comprise a single magnet, the next model two magnets, and so on. The whole series can thus be obtained with a very large number of common parts, which is evidently advantageous in the manufacture in series. 75

The improved electro-magnet that I have just described may be associated with a known electric contact system which closes in the oscillations of the coil in a predetermined direction; if the one end of the coil is energized in a suitable direction by this contact, and if the coil is returned in the direction opposite to the attraction, the coil tends itself to have a to-and-fro movement. The action is like that of electric trembler bells, with the difference that the alternating moving motor thus produced functions with a much greater efficiency than that of house bells. The consumption of electricity and the wear of the electric contact is much less than if an electro-magnet of soft iron were employed. The circuit is also much less inductive and there is no tendency for the formation of sparks as strong as those which are produced with the contacts operating non-polarized electro-magnets. 80 85 90 95

The extent of the displacements can be increased by any known means. The electro-magnet described in the present description can then be applied to the production of alternately moving motors for all applications. We will confine ourselves to mentioning the following applications: 100 105

The electro-magnet can be employed as a polarized relay for closing a contact. By giving to the pole pieces the shape of Figure 9, three positions may be obtained; the middle position of rest corresponding to breakage of the circuit and the extreme positions to right and left corresponding to the closure of two distinct contacts. 110

Employed in an electric bell, the electro-magnet may permit extreme reduction of the consumption of current. Such a bell is specially suitable as an electric clock bell provided with a time contact serving, for example, as a morning alarm. The small battery for operating the movement is sufficient for operating the alarm bell. 115 120 125

In all the known systems for rewinding the weights and driving springs of time mechanisms by means of an electro-magnet or of a periodically closed contact, the electro-magnet may be replaced by the improved device forming the object of the invention. This change permits reduction of the consumption of electricity and avoidance of 130

rapid deterioration of the contact. Further, practice shows that with this device a battery operating with a single element of 1^{v5} is sufficient to obtain rewinding. With electro-magnets actually employed which do not employ a permanent magnet, it is necessary to use batteries of higher voltages.

There is shown by way of example in Figures 12, 13 and 14, an improved construction 10 for an electrically wound clock or watch comprising the electro-magnet forming the object of the invention.

The time mechanism shown in the upper part of Figure 12 comprises a ratchet wheel 15 R₁ which tends to rotate under the action of the pawl arm 1 and of the driving spring 2. This arm returns abruptly backwards from time to time under the action of the electro-magnet so as to assure continuity of the rotation of the ratchet wheel R₁ in the direction of f₁. This wheel controls the gear chain of the clock and of the watch with the speed of the gearing being regulated by an escapement and a balance wheel. (The principle itself 25 of this rewinding system is well known).

The automatic switch which supplies the electro-magnet at the right time is shown separately in Figure 14 which consists of a part 3 stamped in thin silicon sheet metal. 30 Any other magnetic product may be employed possessing very weak hysteresis. This part is movable about the axis O₃ and is disposed adjacent to the pillars P₁ and P₂ or the pillars P₃ and P₄ or adjacent the extensions of these pillars P'₃ and P'₄. It is sufficient for these extensions P'₃ and P'₄ to be strongly magnetized.

The part 3 is of the shape shown in Figure 14, the arcs s₁ t₁, s₂ t₁, s₃ t₃ and s₄ t₃, are 40 of spiral sections so that the rotation of the part causes a change in the reluctance of the magnetic circuit. On the other hand the part 3 is notched and provided with fittings preferably shaped as washers, of which one 4 is 45 of insulating material and the other 5 is of non-oxidizing conducting metal. Between these fittings is a conducting pin 6 fast to the movable coil of the electro-magnet. The diameter of the pin 6 is less than the separation 50 of the fittings 4 and 5.

In the position shown in full lines Figure 14 the part 3 is in unstable equilibrium. In effect this part tends to place itself in the magnetic field so as to reduce the reluctance 55 of the magnetic circuit. Consequently, this part tends to rock to left and to right, the parts of the greatest radius tending to approach the magnetized pillars P'₃ and P'₄.

The parts 3 and the pin 6 are interposed 60 in the electric circuit as shown in Figure 13. One of the ends of the coil B is connected to one of the terminals of the battery, the other end is connected to the pin 6 fixed on a support 7 electrically insulated on the frame 65 of the coil (Figure 12).

The movable part 3 of the switch pivots on the support which is not shown in Figure 12 (for the sake of clearness). It is connected through the intermediary of a very flexible small spiral spring 8 to the other terminal of the battery.

The movement of the pawl arm 1 is transmitted to the coil of the electro-magnet owing to the pin 9 and to the fork 10 solid with the arm 1.

The operation is as follows: (See Figures 12 and 13).

Between the winding actions, the movement of the mechanism is produced by the spring 2. The arm 1 rotates in the direction f₁ and the coil rotates in the direction f'₁.

The shape of the pole pieces B₁ and B₂ of the electro-magnet must be that of Figures 6 or 10 so that the magnetic attraction of the magnet does not interfere in any way with the movement of the time mechanism. The pin 6 bears on the insulating part 4 and the current is interrupted. When the pin 6 solid with the movable coil reaches the position of unstable equilibrium shown in Figure 14, the contact piece 3 rotates suddenly in the direction f₂ and takes up the position indicated in dotted lines in Figure 14.

The conducting pin 6 comes into contact with the conducting fitting 5. The current 95 passes through the coil as indicated in Figure 13.

The coil of the electro-magnet is then displaced suddenly in the opposite direction f₁ and the pawl arm 1 returns back and cocks 100 the driving spring 2.

But at the end of its travel the pin 6 rotates the contact piece 3, and the fitting 5 suddenly leaves the pin 6 so that the circuit is interrupted. The parts then occupy the 105 position shown in Figure 12, and the operation is repeated.

In this device the abrupt displacement of the movable part of the switch is obtained by avoiding the spring mechanisms which are usually employed and which have the disadvantage of acting with considerable friction and of becoming out of order eventually owing to wear of the rubbing parts and jamming.

The invention may be applied to time receivers in which the advance of the hands is controlled by spaced impulses sent out by a master clock.

The electro-magnet forming the object of the invention is particularly suitable for time receivers operating by means of impulses of alternating directions, in which an endeavour is made to reduce the overall dimensions. This result is particularly desirable to obtain in the case of hand controlling mechanisms which are placed behind translucent dials lit from behind by means of electric lamps. The construction of such clocks may be simplified by fixing the mechanism 130

behind and in the centre of the dial; but it is then necessary to reduce to the limit the dimensions of the mechanism, so that the shadow which it produces on the centre of the dial does not adversely affect the visibility of the hands.

Figures 15 and 6 show by way of example how the invention may be applied to the construction of such a time mechanism. The 10 frame of the coil is provided with a control finger 11 which engages in the fork arm 12 solid with the support 13 on which are articulated pawls 14 and 15 acting on the ratchet wheel 16. It is advantageous to adopt pole 15 pieces of such shapes that that armature of the coil tends to be inclined to left or to right, as has been explained with reference to Figure 8.

After each emission of current, the coil 20 mains in place and the magnetic attractions which prevail cause one or other of the pawls 14 or 15 to bear on the locking stops 16 and 17. Thus the hands are maintained in place. Owing to the arrangement shown in Figure 25 16, a ratchet wheel 16 may be employed having a relatively large diameter and all the members may be grouped in a very reduced area corresponding to the external shape of the magnet.

Various modifications may be made in the 30 mechanism described within the spirit of the invention. In particular, instead of the permanent magnet, an electro-magnet may be employed having a winding energized by a 35 continuous or rectified current.

The special shape of the pole pieces which enable the magnetic attraction to be varied with the position of the movable parts according to a selected law can be applied to 40 other types of polarized electro-magnets, and in particular to those which comprise a movable soft iron armature polarized by a permanent magnet, and displaced in relation to other iron parts which are temporarily magnetized, owing to coils of electric wire traversed by intermittent currents.

What I claim is:—

1. Polarized electro-magnet comprising a 50 movable armature carrying an energizing coil provided with polar enlargements consisting of stamped and bent pieces of sheet metal of high permeability and low hysteresis, which armature oscillates in a field of a permanent magnet whose pole pieces consist of cylindrical iron pillars connected to the polar extremities of the magnet by concave sheet metal plates held resiliently between the polar extremities of the magnet and the pillars, and whose concavity is sufficient to accommodate 55 the connections of the coil.

2. Electro-magnet according to claim 1, in 60 which the movable armature consists of two thin plates which are non-magnetic and carry the pivots connected by cross bars, on which 65 the pole pieces of the coil are fitted, these

parts having apertures for the passage of the ends of the core of the coil, assembly being obtained by means of nuts screwed externally on the ends of the core, this armature oscillating in the field of the permanent magnet. 70

3. Polarized electro-magnet according to claim 1, in which the polar enlargements of the armature are shaped as cylindrical surfaces having as axis the axis of rotation of the coil and limited to an arc of small length 75 relatively to the spacing of two adjacent polar pillars of different polarity.

4. Polarized electro-magnet according to claim 1, in which the polar enlargements of the armature are shaped as cylindrical surfaces having as axis the axis of rotation of the coil and extending for an arc of considerable length and, in the position of equilibrium of the coil projecting considerably on either side of those of their points which are nearest to 85 the polar pillars.

5. Polarized electro-magnet according to claim 1, in which the polar enlargements of the armature are shaped as surfaces comprising at the centre a cylindrical part having as 90 axis the axis of rotation of the coil limited to an arc of small length relatively to the space between two adjacent polar pillars of different polarity, connected to cylindrical surfaces of much smaller radius which in the position of equilibrium of the coil project considerably on either side of those of their points which are nearest to the polar pillars. 95

6. Device according to claim 1, in which 100 several identical permanent magnets are disposed side by side and in which the coil is given a length in the direction of its axis of rotation corresponding to the number of magnets employed.

In testimony whereof I have affixed my 105 signature.

MARIUS LAVET.
